UNITED STATES PATENT OFFICE.

EDWIN F. SMITH AND FRANK A. SMITH, OF UNION CITY, CONNECTICUT.

DESIGN FOR A GARMENT-HOOK.

SPECIFICATION forming part of Design No. 26,259, dated November 10, 1896.

Application filed June 22, 1896, Serial No. 596,551. Term of patent 14 years.

To all whom it may concern:

Be it known that we, EDWIN F. SMITH and FRANK A. SMITH, citizens of the United States, residing at Union City, in the county of New Haven and State of Connecticut, have invented and produced a new and original Design for Self-Locking Garment-Hooks; and we do hereby declare the following to be a full, clear, and exact description of the same, reference being had to the accompanying drawings, forming a part thereof.

Our new design of garment-hook is illustrated in the accompanying drawings, in which—

15 Figure 1 represents a plan of the hook, and Fig. 2 represents a side elevation.

The leading feature of the design consists in a garment-hook having a base composed of two straight side portions, a bill substantially parallel therewith, and a tongue lying between the two base portions, the tongue being straight along its under side and having a narrow rib or knob rising from its upper surface under the straight bill.

25 1 denotes the bill of the hook; 2, the base;

3, the attaching-eyes, and 4 the tongue, the latter extending parallel with and between the two side portions of the base and having the narrow rib or knob 6 rising from the upper surface of its forward portion. The under surface of the tongue is straight and parallel with the under surface of the base 2, while the upper surface of the elongated narrow top knob 6 is rounded, as indicated in Fig. 2.

30 The bill 1 is flattened and is substantially parallel with the base 2 in side elevation, as shown in Fig. 2, and in plan is open above the knob or rib 6.

35 We claim—

The design for a garment-hook substantially as shown and described.

In testimony whereof we affix our signatures in presence of two witnesses.

EDWIN F. SMITH.
FRANK A. SMITH.
